UNITED STATES PATENT OFFICE

EARL S. PRINCE, OF STERLING, ILLINOIS, ASSIGNOR TO PRINCE & COMPANY, OF STERLING, ILLINOIS, A COPARTNERSHIP COMPOSED OF EARL S. PRINCE AND EARL H. PRINCE

DESIGN FOR A MERCHANTISE BOOTH

Application filed June 13, 1930. Serial No. 36,043. Term of patent 14 years.

To all whom it may concern:

Be it known that I, EARL S. PRINCE, a citizen of the United States, residing at Sterling, in the county of Whiteside and State of Illinois, have invented a new, original, and ornamental Design for a Merchandise Booth, of which the following is a specification, reference being had to the accompanying drawing, forming part thereof.

In this drawing:

I claim:

The ornamental design for a merchandise booth, as shown.

EARL S. PRINCE.
